UNITED STATES PATENT OFFICE.

CHARLES M. MOHLER, OF KENOSHA, WISCONSIN.

CARBURETER FOR HYDROCARBON-ENGINES.

SPECIFICATION forming part of Letters Patent No. 759,001, dated May 3, 1904.

Application filed July 27, 1903. Serial No. 167,103. (No model.)

To all whom it may concern:

Be it known that I, CHARLES M. MOHLER, a citizen of the United States, residing at Kenosha, in the county of Kenosha and State of Wisconsin, have invented certain new and useful Improvements in Carbureters for Hydrocarbon-Engines, of which the following is a specification.

My invention relates to carbureters for hydrocarbon-engines, more particularly to devices comprising adjustable elements constructed and arranged to supply gasoline and air in suitable quantities, mixture, and proportions by atmospheric pressure into a cylinder or chamber exhausted by the operation of a gas-engine, the mixture being ultimately exploded and constituting the source of power.

One object of my invention is to provide a carbureter that will enable a sufficient amount of gasoline and air for starting purposes to be drawn in by a relatively slow movement of the engine derived from outside sources to enable it to continue the movement by its own explosions, rendering unnecessary the operating of the gasoline-supplying device by hand for the initial impulses.

Another object of my invention is to produce a carbureter having a diluting-valve automatically opened when the engine is to be stopped and upon shutting off the throttle-valve admitting the explosive mixture in order that the exhausting effect of the final piston movements may be minimized by free ingress of air, thereby preventing the drawing in of gasoline, which, not being exploded to drive the engine, is wasted.

A further object of my invention is to fashion a diluting-valve for a carbureter that is fully responsive to changing pressures brought about by the variable speed of the engine and which when properly adjusted governs the amount and quality of the explosive mixture supplied at the lowest and up to the highest speed.

It is also an object of my invention to make a carbureter in which the gasoline is sprayed through a number of ducts that surround a central air-passage, to the axis of which the ducts are inclined, thus directing sprays of

gasoline across the column of air and effecting a most intimate mixture between them.

An additional object of my invention is to create a carbureter wherein the spraying-ducts do not extend downwardly far beneath the gasoline-surface in the fluid-receptacle, thereby allowing a considerable fluid volume below the lower mouths of the ducts to collect water and foreign matter and permitting the relatively pure gasoline to rise into the ducts.

I accomplish the objects above recited by constructing and associating the parts as illustrated in the accompanying drawings, of which—

Figure 1 is a vertical sectional view showing all the parts assembled. Fig. 2 is an end view looking into the conical throttle-valve which is detached. Fig. 3 is an outside view of the conical valve detached, the apex being toward the observer; and Fig. 4 is an end view from the right of the operating-ring detached and the starting and stopping lever pivotally carried by the ring. Fig. 5 represents a vertical section of the operating-ring upon a plane including its axis. In this view the operating-lever has been added to indicate its position with relation to the cam-lug upon the inside of the ring. Fig. 6 is an end view of the ring and side view of the lever from the left.

Like characters refer to like parts in the several views.

Each element is separately mentioned and its individual office, together with the mode of operation of the whole, is fully explained herein.

Inclosing the details and forming the body of the invention is a casing consisting of the hollow cylindrical portion marked 1, by way of which the mixed air and gasoline-spray passes to the engine and which is actually the mixing-chamber for air entering through the diluting-valve and the air overcharged with gasoline entering by way of the combining-tube 2. Tube 2 has at its upper end a threaded connection with cylinder 1, and near the lower end it is extended horizontally into a dish-flange 3, that possesses near its

rim a circumferential seat or shoulder 4, occupied by a ring-gasket 5, that directly supports the cylindrical wall 6 of the float-chamber 7. Wall 6 may be of transparent glass 5 to render always visible the quantity of fluid within, or it may be of metal, as preferred. A corresponding seat 8 is formed on a suitable extension 9 of cylinder 1, and another gasket or packing ring 10 is placed in the seat 10 and upon the upper edge of the wall 6. As the combining-tube 2 is screwed into cylinder 1 both gaskets are compressed and tight joints are made with the wall of the float-chamber. While I have illustrated a float 15 and chamber and prefer to employ such devices to maintain a constant level of gasolene, they are not absolutely essential. Any suitable contrivances adapted to serve the gasolene to the ducts might be used with my invention.

As customarily fashioned the combining-tube 2 has a relatively constricted portion immediately below the ducts 11, and the upper mouths of the ducts open through an interior 25 shoulder 12, and from the shoulder up the diameter of the tube is increased. The ducts incline downwardly and outwardly, and their lower mouths, located about midway of the depth of the float-chamber leave a considerable 30 depth of gasolene beneath for accumulated water and impurities. The broken line $y_2 z$ marks the mean level of the pure gasolene. Combining-tube 2 opens at the bottom into an air-receiver 13, and a heater 14, that may be connected with the exhaust, is arranged to heat receiver 13 and air passing through it. An air-pipe 15, opening into the receiver, also opens into the connection 16, joined to and constituting a continuation of cylinder 1. Through connection 16 air is drawn to the receiver and combining-tube and to the diluting-valve also.

Within the cylinder 1, first mentioned, the working parts of my invention are located.

No. 17 designates the conical throttle-valve 45 seat, having its base-ring 18 situated and secured in the interior annular shoulder 19 of the cylinder. A correspondingly conical rotary throttle-valve 20 (see Figs. 2 and 3) fits the seat internally, and both valve and seat 50 have any convenient number of registering ports of large size by reason of the conical form, through which the explosive mixture passes to the engine and by which the flow of that mixture is controlled. A bushing 21 is secured in the smaller open end of valve-seat 17, and the aperture 22 through the bushing, which I term the "slow" port, may be varied in size for different motors by the thickness of the bushings. The base-ring of the 55 conical valve 20 possesses the recesses 23, (see Fig. 2,) and these recesses engage teeth 24, shown in broken lines in Fig. 6 as formed on the front of the operating-ring 25, which meets the base-ring of the valve edge to edge, 60 as drawn in Fig. 1. In a recess 25^a of suit-

able size and pivotally attached to the ring is the operating bell-crank lever 26, the normal position of which, as illustrated in Fig. 6, against one end of recess 25^a is maintained by a C-spring 27. The pivot-screw securing 70 the lever to the lug 28 of the operating-ring is marked 29, Fig. 4.

The diluting or puppet valve 30 is centrally located, as shown, and is provided with a seat 31, formed in the diaphragm 32 of the interior fitting 33. Valve 30 is loose upon rod 34, which has a head 35 and threaded end 36, and between the head and valve a spiral spring 37 encircles the rod and constantly tends to press the valve toward its seat. Normally valve 30 75 is unseated to a predetermined extent intended to pass diluting-air in amount necessary at average speed or thereabout. To keep the valve properly unseated, it is acted upon either directly or through the interposed washer 38, 80 Fig. 1, by a sleeved plunger or valve-stop 39, reciprocative in the hollow guiding-cylinder 40 and governed by a spiral spring 41, which overcomes spring 37. Spring 41 is compressed 85 between the shoulder 42 of the plunger and 90 the bottom or head 43 of the guide-cylinder by nut 44 and jam-nut 45 outside guide 40 on the threaded end 46 of the plunger-sleeve. The nuts therefore make it practicable to unseat valve 30 to the extent required. Rod 95 34 is adjusted by nut 47 against the outer end of the plunger-sleeve, and all the nuts are accessible through the open end of connection 16.

In Fig. 1 it is shown that a pivoted angular lever 48 has its lower end engaged by a slot 49 in the valve-stop 39, and it is believed to be clear that if the upper end of lever 48 is depressed the valve-stop will be moved to the right, and spring 37 will seat the valve. This operation takes place on starting the engine 100 by turning the operating-ring to the right until the cam-lug 50, Fig. 3, encounters and turns down lever 48. Here it will be noted that the stop 51, (see Figs. 2 and 3,) projecting interiorly from the stationary conical 105 valve-seat 17, passes into a groove 52 on the outside of one of the divisions of valve 20 and permits the turning of the valve to the right past its maximum open position. Valve 30 seats and the ports of the throttle-valve are 110 partly closed. All air must now come in by way of combining-tube 2, which being relatively small enables the operator to cause a sufficient partial vacuum when turning the motor over comparatively slowly by hand to 115 draw in gasolene enough for a start. When the motor has started, the lever is moved to the left, opening the throttle to its maximum or less, as desired. To stop the engine, lever 26 is turned to the left until stop 51 meets the 120 approaching division of the valve at the point marked A. Further movement of the operating-ring 25 is arrested; but lever 26 may by additional pressure be turned on pivot-screw 29, closing C-spring and raising the lower end 125 130

of the lever against the upper end of lever 48 and lifting it into the recess 53, formed to receive it in operating-ring 25. (See Fig. 4.) The lower end of lever 48 is thus forced forward, and valve 30 is moved farther from its seat, increasing largely the path to outside air. All ports of the throttle-valve are now closed but the permanently-open slow port 22. The air exhausted by the final movements of the engine through the slow port is almost instantly supplied through the widely-opened diluting valve, and the little difference in pressure does not cause the gasolene to enter tube 2 to be wasted unused.

Having thus described my invention, what I claim, and desire to secure by Letters Patent of the United States, is—

1. In a carbureter, the combination of devices for spraying gasolene, a diluting-valve normally unseated and held yieldingly, and means for seating said diluting-valve.

2. In a carbureter, the combination with devices for spraying gasolene, of a diluting-valve normally unseated and held yieldingly, means for seating said diluting-valve, and contrivances adapted to move said valve from its normal unseated position whereby additional air is admitted.

3. In a carbureter, the combination of a diluting-valve normally unseated and held yieldingly, adjusting devices constructed to vary the distance between said valve and its seat, and means for seating the valve.

4. In a carbureter, the combination of a diluting-valve normally unseated and held yieldingly, adjusting devices constructed to vary the distance between said valve and its seat, means for seating the said valve, and contrivances adapted to move said valve from its normal unseated position whereby additional air is admitted.

5. In a carbureter, the combination of a throttle-valve, an operating-lever connected with the valve, a diluting-valve, and contrivances actuated by the said lever and arranged to move said diluting-valve from its seat.

6. In a carbureter, the combination of a throttle-valve having a permanently-open slow port, an operating-lever connected with the said valve, a diluting-valve, and contrivances actuated by the said lever upon closing the throttle-valve and arranged to move said diluting-valve from its seat.

7. In a carbureter, the combination of a throttle-valve having a permanently-open slow port, an operating-lever connected with

the said valve, a diluting-valve normally unseated and held yieldingly, valve-operating devices actuated by moving said lever in one direction and adapted to seat said diluting-valve, said valve-operating devices being operated by said lever and arranged to move said diluting-valve from its seat when the lever is turned oppositely.

8. In a carbureter, the combination of a rotary conical throttle-valve and fixed seat having a permanently-open slow port, an operating-ring connected with said valve, means whereby said ring can be moved from the exterior, a diluting-valve held yieldingly, and devices actuated by the movement of said operating-ring and arranged to seat said diluting-valve.

9. In a carbureter, the combination of a rotary conical throttle-valve and fixed seat having a permanently-open slow port, an operating-ring connected with said valve, a diluting-valve normally unseated and held yieldingly, valve-operating devices actuated by the movement of said operating-ring and arranged to seat said diluting-valve, means whereby said ring can be rotated from the exterior, said devices being actuated by said ring-rotating means and arranged to move said diluting-valve from its seat.

10. In a carbureter, the combination of a rotary conical throttle-valve and fixed seat having a permanently-open slow port, a stop arresting said valve in one direction at its closed position, an operating-ring connected with said valve, a diluting-valve normally unseated and held yieldingly, valve-operating devices actuated by the movement of said ring and arranged to seat said diluting-valve, a bell-crank lever pivotally attached to said ring, means for limiting the pivotal movement of the lever in one direction causing it to rotate the ring, a spring arranged to partially resist the pivotal movement of said lever in the opposite direction whereby said conical valve is rotated to said stop and extra movement of the lever permitted, said lever during its extra movement acting upon said valve-operating devices to move said diluting-valve from its seat.

In testimony whereof I affix my signature in presence of two witnesses.

CHARLES M. MOHLER.
